* cited by examiner

Primary Examiner—Doris Clark(74) *Attorney, Agent, or Firm*—Nickolas E. Westman; Westman, Champlin & Kelly, P.A.(57) **CLAIM**

The ornamental design for a ladder top side rail extension set, as shown and described.

DESCRIPTION

FIG. 1 is a left side perspective view of left and right ladder side rail top extension embodying our new design with a ladder represented in dotted lines for illustrative purposes; FIG. 2 is a right side perspective view of the showing in FIG. 1;

FIG. 3 is a left side view of a left ladder side rail top extension set embodying our new design;

FIG. 4 is a right side view thereof;

FIG. 5 is a top plan view thereof; and,

FIG. 6 is a bottom plan view thereof; the the right ladder side rail top extension set is a mirror image of the left ladder side rail top extension set and the dotted line representations form no part of the claimed design.
